(57) **CLAIM**

The ornamental design for a display screen with graphical user interface, as shown and described.

DESCRIPTION

The FIGURE is a front view of a display screen with graphical user interface showing our new design.

The broken line illustrating a display screen forms no part of the claimed design. The broken lines illustrating portions of the graphical user interface form no part of the claimed design. The broken line representing an electronic device illustrates environmental structure and form no part of the claimed design.
